(57) **CLAIM**

The ornamental design for a set of seats for a commercial aircraft passenger cabin, as shown and described.

DESCRIPTION

FIG. 1 is a front-left side perspective view of a set of seats for a commercial aircraft passenger cabin according to a first embodiment of my design;

FIG. 2 is a top plan view thereof;

FIG. 3 is a front-right side perspective view of a second embodiment being a mirror image of the set of seats shown in FIG. 1;

FIG. 4 is a top plan view of the set of seats shown in FIG. 3;

FIG. 5 is a front-left side perspective view of the set of seats of FIG. 1 shown in a commercial aircraft passenger cabin; and,

FIG. 6 is a top plan view of the set of seats and cabin shown in FIG. 5.

Bottom plan, rear, left side and right side elevation views are not part of the claimed design.

Throughout the Figures, the broken lines showing environment or structure are for illustrative purposes only and form no part of the claimed design.

As shown in the Figures, the seat layout (the positioning of each with respect to the other) is within the scope of the claimed design.
